UNITED STATES PATENT OFFICE.

HERMAN NATER, OF CLEVELAND, OHIO.

NON-REFILLABLE BOTTLE.

No. 903,398.

Specification of Letters Patent.

Patented Nov. 10, 1908.

Application filed May 22, 1908. Serial No. 434,275.

To all whom it may concern:

Be it known that I, HERMAN NATER, a citizen of the United States, residing at Cleveland, in the county of Cuyahoga and State of Ohio, have invented certain new and useful Improvements in Non-Refillable Bottles, of which the following is a specification.

My invention relates to improvements in non-refillable bottles, and is specially designed for use by manufacturers of or dealers in certain special brands of liquors, bitters and the like, so as to enable them to guard against the refilling of a bottle with an imitation of their particular brand of liquor, etc. after the genuine article has been removed.

The primary object of the invention is to provide a generally improved device of this class, which will effectually close and seal the bottle for shipment and for actual use, so as to prevent the unlicensed picking or opening of the stopper or closure for the purpose of refilling the bottle with a spurious article.

Another object of the invention is to provide a sheet metal device of this class, which may be readily attached and secured to any bottle now in use, and which will be exceedingly simple in construction, cheap of manufacture, and efficient in use.

With these ends in view, the invention consists in the novel construction, arrangement, and combination of parts, hereinafter described, illustrated in the accompanying drawings, and particularly pointed out in the appended claims.

Referring to the drawings, forming a part of this specification, Figure 1, is a side elevation of the preferred form of stopper applied to an ordinary bottle neck. Fig. 2, a longitudinal sectional view of the same. Fig. 3, a longitudinal sectional view of a modified form of same. Fig. 4, a top plan view of the preferred form of stopper shown in Fig. 1. Fig. 5, a cross sectional view taken through line 5—5, of Fig. 2. Fig. 6, a cross-sectional view taken through line 6—6, of Fig. 2. Fig. 7, a side elevation, partly in section, of the removably-mounted cup-valve used in connection with the preferred form of stopper. Fig. 8, a side elevation of the improved detachable operating nozzle-head. Fig. 9, a cross sectional view taken through line 9—9, of Fig. 3.

Similar numerals of reference designate

like parts throughout all the figures of the drawings.

The main cap, or body portion 1, is cylindrical in form and is adapted to be mounted entirely within the bottle neck 2, as shown in Fig. 1, or resting upon the tip of the same as shown in Fig. 3, in which case it is secured thereto by means of a second cap or hood portion 3, of sheet metal adapted to fit down over the tip of the bottle and be secured, clamped or sealed about the same, the lower portion forming a circumferentially-extending rib 4 for taking over the circumferential rib 5, of the bottle neck, and, in the present instance, an inwardly-extending circumferential rib 6, takes into the annular recess 5^a, of the bottle neck. The upper end of the hood 3, is provided with an inwardly-extending securing flange 7, which is bent inwardly and takes over a circumferential flange or rib 8, at the lower end of the sheet metal cap 1. When the main body portion 1, is formed for insertion within the mouth of the bottle neck as shown in Figs. 1 and 2, of the drawings, it is preferably provided with an annular shoulder or flange 1^a, adapted to rest upon the tip of the bottle neck.

The main cap or body portion 1, comprises an upper or cup-valve receiving portion 9, and a lower or valve-inlet portion 10, adapted to extend into the neck of the bottle.

The upper or cup valve receiving portion is provided about its inner periphery with spiral grooves or threads 11, and the lower or valve-inlet portion is provided with an annular shoulder or valve-seat 12, terminating in a reduced depending portion 13. The upper or cup receiving portion 9, is adapted to receive and contain a cup-valve comprising an upper cylindrical portion 14, having its outer periphery provided with oppositely-disposed studs 15, adapted to take into and fill the spiral grooves or threads 11, and a reduced depending or valve-head portion 16, provided with a plurality of circumferentially-extending radial inlet-openings 17. The beveled or conical shaped valve-head 16^a, is adapted to impinge or be seated upon the annular shoulder or valve-seat 12, when the cup valve is raised or lowered by the means hereinafter described.

The radial inlet-openings 17, are normally closed to prevent the refilling of the bottle, by the pouring in of liquids from without, by means of vertically movable valves which

may either take the form of a shell portion having a truncated cone-shaped head 18, as shown most clearly in Figs. 2, and 7, of the drawings, or the form of a horizontal disk-valve 19, as shown most clearly in Figs. 3 and 9, of the drawings.

In order to prevent any tampering with, or unauthorized raising of, the vertically-movable valves, a disk 20, is mounted in the 10 cup-valve portion above the vertically-movable valves and said disk may either take the form shown in Figs. 2 and 6, of the drawings in which it is provided with a series of openings 21, or the form shown in 15 Figs. 3, and 9, in which it is provided with a single central opening 22.

It will be seen that the base of the truncated cone-shaped head 18, is provided with a central opening 23, having its periphery 20 intersected by a series of radial openings 23^a, as shown most clearly in Fig. 5, of the drawings, while the disk-valve 19, is provided with a plurality of radially-extending arms 24, which abut against the cup valve body 25 and provide intermediate inlet-openings 24^a.

As a means for providing a suitable liquid discharge-head or nozzle and also for providing means for raising and lowering the cup valve carrying the valve-head portion 30 16, a nozzle-head is provided, comprising a discharge-nozzle or dome-portion 25, having the main discharge-opening 26, and a depending cylindrical portion 27, adapted to frictionally fit within the upper cylindrical 35 portion or rim 14, and when in its normal position, to revolve said cup-valve by means of oppositely-disposed notched recesses 28, receiving and taking over oppositely-disposed inwardly-extending stud-pins 29, on 40 the rim 27, of the cup-valve portion. An intermediate flange or milled rim portion 30, is formed on the discharge head by means of which the latter may be manipulated.

When the cup-valve is raised by means of 45 the milled head of the discharge nozzle the liquid from within the bottle will be permitted to flow out through the depending-portion 13, and thence through the radial inlet-openings 17, and into the annular space 50 13^a, the valves being in their open position by reason of the position of the bottle in pouring (see for example the position of the truncated cone-shaped head 18, of the valve in Fig. 7), and the liquid thence flows 55 out through the body of the cup-valve and out through the main discharge opening 26, of the discharge nozzle. A stopper annulus 31, preferably formed of a paper composition, is formed about the main body portion 60 1, within the bottle neck, forming a packing to prevent leakage. It will also be understood that the form of cap or body portion shown in Figs. 1 and 2, is driven so firmly 65 home and is so firmly secured that it will be impossible to remove the same through the

mouth of the bottle without so mutilating or otherwise injuring the parts as to cause a detection of the unauthorized meddling or tampering with the parts.

In order to prevent the removal of the 70 cup-valve, after the parts are assembled and placed in the mouth of the bottle, the spiral grooves or threads 11, are formed so as not to extend entirely to the top of the upper portion 9, of the valve-cap and the cup-valve 75 14, is first inserted in the valve receiving portion 9, of the cap body, after which the oppositely-disposed studs 15, are pressed outwardly by means of a suitable instrument and into the spiral grooves or threads 11. 80 In view of this construction it is obvious that the cup-valve cannot be entirely unscrewed or removed from the cap-body by reason of the fact that one of the studs 15, will form a stop to engage the upper terminal end of the spiral groove 11, thus preventing the entire removal of the cup-valve.

Having thus described my invention, what I claim and desire to secure by Letters Patent is,—

90

1. A non-refillable bottle, consisting of a main cap or body comprising a cup-valve receiving portion and a valve inlet portion, a communicating cup mounted in said cup valve receiving portion and provided with a depending valve head adapted to close said valve inlet portion, a nozzle-head extending above said cap and communicating with said cup-valve, and a valve movably-mounted in said cup-valve and normally closing said valve-inlet portion. 95

2. A non-refillable bottle, comprising a cap body having a cup-valve receiving portion and a valve-inlet portion, a communicating cup-valve mounted in said valve receiving portion and provided with a valve-head adapted to close said valve-inlet portion, and a valve mounted in said cup-valve and normally closing the communication between said cup-valve and said valve-inlet portion. 105

3. A non-refillable bottle, comprising a cap body provided with an annular valve-seat terminating in a valve-inlet portion, a cup-valve provided with a valve-head and a plurality of inlet-openings, and a vertically-movable valve normally closing said inlet-openings except when in its elevated or open position. 115

4. A non-refillable bottle, comprising a cap body provided with an annular valve-seat 120 and a depending valve-inlet portion, a cup-valve threaded in said cap body and having a reduced portion provided with inlet-openings and terminating in a valve-head, a valve mounted in said reduced portion and normally closing said inlet-openings, and a perforated disk carried in said cup-valve above said valve normally closing said inlet-openings.

5. A non-refillable bottle, comprising a cap 125

- body provided with a valve-seat terminating in a reduced valve-inlet portion, a cup-valve having a reduced portion terminating in a valve-head and provided with radial inlet-
5 openings above said valve-head, and a perforated disk - valve mounted in said cup-
valve and provided with a hollow truncated cone-shaped head normally closing said inlet-openings.
- 10 6. A non-refillable bottle, comprising a cap body provided with a valve-seat and a depending valve - inlet portion, a cup - valve threaded in said cap - body and provided with a conical portion having inlet-openings and terminating in a valve-head, a disk-valve mounted in said cup-valve and provided with a hollow truncated cone - shaped head normally closing said inlet-openings, a perforated disk mounted in said cup-
15 valve above said disk-valve.
- 20

7. A non-refillable bottle, comprising a cap provided with a valve-seat and a valve-inlet portion, a cup-valve threaded in said cap-
body and provided with a conical portion having inlet-openings and terminating in a 25 valve-head, a disk-valve mounted in said cup-valve and provided with a hollow truncated cone - shaped head normally closing said inlet-openings, a perforated disk mounted in said cup-valve above said disk-valve, 30 and a communicating nozzle - head removably-mounted in said cup-valve and normally engaging with said cup-valve when revolved.

In testimony whereof I have affixed my 35
signature, in presence of two witnesses.
